UNITED STATES PATENT OFFICE.

GEORGE S. WARD, OF NEW YORK, N. Y., ASSIGNOR TO WARD BAKING COMPANY, OF NEW YORK, N. Y., A CORPORATION OF NEW YORK.

DESIGN FOR A PARAFFIN-PAPER WRAPPER FOR A LOAF OF BREAD.

48,878.

Specification for Design.

Patented Apr. 11, 1916.

Application filed September 16, 1914. Serial No. 862,113. Term of patent 14 years.

To all whom it may concern:

Be it known that I, GEORGE S. WARD, a resident of the city, county, and State of New York, have invented a new, original, and ornamental Design for a Paraffin-Paper Wrapper for a Loaf of Bread, of which the following is a specification, reference being had to the accompanying drawings, forming part thereof.

Figure 1 represents in perspective view a loaf of bread wrapped in a paraffin-paper

wrapper showing my new design; and Fig. 2 represents a view of the said loaf reversed to expose the other two sides and the other end.

I claim:

The ornamental design for a paraffin-paper wrapper for a loaf of bread, as shown.

GEORGE S. WARD.
